UNITED STATES PATENT OFFICE.

OTIS L. MALLORY, OF BEARDSTOWN, ILLINOIS.

SASH-LOCK.

1,197,219.

Specification of Letters Patent. Patented Sept. 5, 1916.

Application filed September 17, 1914. Serial No. 862,147.

To all whom it may concern:

Be it known that I, OTIS L. MALLORY, a citizen of the United States, residing at Beardstown, in the county of Cass and State 5 of Illinois, have invented a new and useful Sash-Lock; and I do hereby declare the following to be a full, clear, and exact description of the invention, such as will enable others skilled in the art to which it appertains to make and use the same.

This invention relates to a new and useful improved sash lock.

An object of the invention is the provision of a sash lock so constructed as to lock both sashes in closed positions, or in 15 different open positions, so as to prevent the sash from being unlocked from the outside.

In practical fields the details of construction may be subjected to alterations, falling 20 within the scope of what is claimed.

The invention comprises further features and combination of parts, as hereinafter set forth, shown in the drawings and claimed.

In the drawings:—Figure 1 is a view in 25 perspective of a fragmentary portion of a window frame and the upper and lower sashes showing the improved lock applied. Fig. 2 is a sectional view through the window frame and the upper sash, showing the 30 lower sash in edge elevation and the sash lock in plan view. Fig. 3 is an enlarged detail view of the sash lock slide removed from its guide member. Fig. 4 is a perspective view of the guide member.

Referring more especially to the drawings, 1 designates the usual window frame having the conventional construction of guides 2 and 3 for the upper and lower sashes 4 and 5. Secured to the parting strip 40 6 of the window frame by means of screws 7 is a strip 8 having a series of notches 9. The strip 8 is provided with a metal plate 8^a pressed or shaped to form notches 9^a to fit the notches of the strip 8. Carried by 45 the upper sash 4 and fastened thereto is a plate 10 having a series of openings or apertures 11. Secured to the upper right hand edge of the lower sash 5 by means of suitable screws (not shown, which are de- 50 signed to pass through the openings or holes or apertures 12) is a plate 13 having guide flanges 14, which overlie the flanges 15 of the sash locking plate 16. The guide flanges 14 are beveled as shown at 17 to engage the

beveled or inclined portion 18 of the central arched portion 19 of the sash locking plate. This sash locking plate is arched, in order to lessen the friction between the same and the upper surface of the plate 13, and also in order to escape contact with the 55 screw heads (not shown), which are designed to be countersunk in said openings or apertures 12. The sash locking plate at one end is provided with a laterally extending tongue 20, which is designed to enter 60 any one of the notches 9^a of the plate 8^a, to hold the lower sash in adjusted open or closed positions. Also rising upwardly and projecting in a lateral direction of the sash locking plate 16, but in a lateral direction at 70 right angles to the tongue 20 is an elongated lug 22, designed to enter any one of the apertures or openings 11 in the plate 10 carried by the upper sash, so as to lock the two sashes relative to each other, at the 75 same time the tongue 20 engages one of the notches 9^a of the plate 8^a, thereby holding the sashes in adjusted positions relative to the window frame. By this construction of sash locking means, the sashes may be held 80 locked in open positions, sufficient to permit of the requisite ventilation, and at the same time prevent the intrusion of a burglar. Rising from the arch of the sash locking plate is a thumb or hand piece 24, by 85 which the plate may be adjusted manually. When the sash locking plate 16 is thrown or moved to lock the sash, the lug 20 engages the notches 9^a of the plate 8^a.

The invention having been set forth, what 90 is claimed as new and useful is:—

In a sash lock, the combination of a window frame and the upper and lower sashes, of a notched strip carried by the parting strip of the frame, a strip having a plurality of spaced apertures carried by the inner face of one of the side rails of the upper sash and at right angles to the notched strip, a plate secured transversely to the upper edge of the upper rail of the lower 100 sash in a plane extending toward the apertured strip, said plate having side overhanging guide flanges, a sash locking plate provided with lateral elongated side flanges engaging under said guide flanges, whereby 105 the locking plate may move transversely of the upper sash, one end of said locking plate having an angular lug extending upwardly

and protruding beyond the end of the locking plate and designed to enter any one of the apertures of the apertured strip, and a laterally extending tongue at right angles to the lug being carried by the locking plate to engage any one of the notches of the notched strip, whereby the upper and lower sashes

are held in adjusted positions relative to each other and in different positions of the frame.

In testimony whereof I have signed my name to this specification.

OTIS L. MALLORY.
